UNITED STATES PATENT OFFICE.

HAROLD A. GREENWALD, OF DETROIT, MICHIGAN, ASSIGNEE TO THOMAS C. WHITE-
HEAD, OF DETROIT, MICHIGAN.

CONDENSER FOR REFRIGERATING APPARATUS.

Application filed March 21, 1927. Serial No. 177,093.

The invention relates to refrigerating apparatus and more particularly to improvements for effecting the condensation of the refrigerating medium.

In the present state of the art of domestic refrigeration it is usual to design the apparatus so that the desired low temperature may be maintained in the refrigerator compartment by an intermittent circulation of the refrigerant controlled and regulated by a suitable thermostat. It is also the usual practice to effect the condensation of the compressed refrigerant by circulating air at room temperature through condensing coils by means of a fan or equivalent device. The object of my invention is to increase the condenser efficiency by supplementing the air cooling means with additional cooling means so incorporated in the apparatus as to be practical in a domestic type installation.

For this purpose I have designed a condensing apparatus in which part or all of the conduits for the refrigerant are arranged in thermal contact with certain chemical substances having hydroscopic or deliquescent properties, or, in other words, having the property of absorbing moisture from the atmosphere. One substance particularly suitable is calcium chloride. When this substance is arranged in thermal contact with the condenser coils and the refrigerating apparatus is in the portion of its intermittent cycle where the refrigerant is not circulating, the calcium chloride continuously absorbs moisture from the atmosphere. When the circulation through the condenser again commences, the heat from the compressed refrigerant causes the absorbed moisture in the calcium chloride to be reevaporated and this evaporation results in a cooling effect which assists in the condensation of the refrigerant. Thus if the condenser is subjected to air cooling in the usual manner and also arranged in thermal contact with a hydroscopic or deliquescent substance, the condensation of the refrigerant is accomplished by the combined cooling effects of the circulating air and the evaporation of the absorbed moisture. The fact that the refrigerating system is intermittently operated permits the proper functioning of the calcium chloride as an additional cooling agent whenever its cooling effect is required. It acts as a carrier for the moisture which is alternately absorbed and reevaporated. The absorption of the moisture is ac-

companied by a heating effect, but as this occurs during the period when the refrigerant is not circulating, the heat acquired by the condenser is dissipated by radiation and is not absorbed to any material degree by the refrigerant itself. On the other hand, when the refrigerant is in circulation the temperature is materially lowered by the cooling effect and the refrigerant loses part of its heat to the evaporated moisture.

My invention is not limited in application to any particular type of refrigerating apparatus, but in order to more clearly illustrate a practical embodiment of the invention reference is made to the accompanying drawings, wherein

Figure 1 represents a refrigerating system of the compression type to which my invention may be applied;

Figure 2 is a cross section through a condenser embodying my invention;

Figure 3 is a modified arrangement for obtaining an additional cooling effect in a refrigerant condenser.

Referring now to the drawings, 1 represents an electric motor, 2 a suitable compressor connected thereto by a shaft 3 on which is mounted a fan 4. 5 is a condensing coil connected by a conduit 6 with the outlet of the compressor and having at its base a reservoir 7 for the condensed refrigerant. The condenser 5 is cooled by a circulation of air promoted by the fan 4 and to aid in the cooling there is preferably provided a hood 8 surrounding the condenser, compressor and fan. 9 represents diagrammatically a refrigerator compartment in which is located the refrigerating or expansion coils 10, the latter being connected by a conduit 11 with the reservoir 7 and by the conduit 12 to the inlet of the compressor. A suitable expansion valve 13 and compressor valve 14 may be arranged in the usual manner. For controlling the operation of the motor 1 a suitable thermostatic switch 15 is arranged in any convenient location in the refrigerator. This switch is so designed as to operate the motor when the temperature in the refrigerator rises to a predetermined value and to stop the motor when the temperature is lowered to any predetermined value.

The calcium chloride or other equivalent substance is preferably arranged on the outer surfaces of the coils of the condenser and it may be retained in thermal contact there-

with by various expedients. In the preferred embodiment of the invention the calcium chloride is applied to the coils in the form of a paint, thus forming an adherent layer 16 surrounding the coils 17. With this arrangement the surface area of the condenser is not diminished in size, but all of the heat transferred from the refrigerant to the surrounding air must pass through the walls 10 of the coils 17 and the layer of calcium chloride. Due to the hygroscopic or deliquescent properties of the layer or coating 16 the coils 17 are in effect provided with a surrounding reservoir for a cooling fluid, which reservoir 15 is automatically replenished by the chemical action of the material in absorbing moisture from the atmosphere.

In Figure 3 a considerably modified form 20 of my invention is illustrated, for in this arrangement instead of employing calcium chloride as a solid substance surrounding the coils, it is dissolved in water forming a solution in which the lowermost coils of the condenser are immersed. Thus, as shown, there 25 is provided a suitable container 18 filled with a calcium chloride solution to immerse a certain portion of the condenser coils. In this construction the cooling is due to the combined effects of the air circulating over the 30 exposed condenser coils and the evaporation from the solution in contact with the remain-

ing coils during the running periods of the machine.

What I claim as my invention is:

1. The method of operating a cooling system which consists in intermittently passing a heated medium through a cooling conduit having a deliquescent substance in thermal contact therewith, producing a cooling effect during the passage of said heated medium by evaporation of the liquid in said deliquescent substance and absorbing moisture in said substance when said heated medium is not in circulation. 35

2. A condenser comprising a conduit for the medium to be cooled and a deliquescent substance in thermal contact with said conduit. 40

3. The combination with a refrigerating system having a compressor, condenser, expansion coils and means for intermittently circulating the refrigerating medium, of a deliquescent substance associated with said condenser for assisting in the condensation 50 of the refrigerating medium. 55

4. A condenser comprising a conduit for the medium to be cooled and solid calcium chloride arranged in thermal contact with said conduit.

In testimony whereof I affix my signature.

HAROLD A. GREENWALD.
